(57) **CLAIM**

I claim the ornamental design for a doll with gem stone, as shown and described.

DESCRIPTION

FIG. 1 is a front perspective view showing my new design;

FIG. 2 is an enlarged view of the gem stone;

FIG. 3 is a left side elevational view, the right side being a mirror image thereof;

FIG. 4 is a rear perspective view thereof;

FIG. 5 is a top perspective view thereof; and,

FIG. 6 is a bottom perspective view thereof.
